UNITED STATES PATENT OFFICE.

CHARLES DOERING, JR., AND HENRY H. DOERING, OF OAK PARK, ILLINOIS.

APPARATUS FOR DISPENSING DRINKING-CUPS AND BEVERAGES.

1,252,413.

Specification of Letters Patent.

Patented Jan. 8, 1918.

Application filed January 4, 1915. Serial No. 512.

To all whom it may concern:

Be it known that I, CHARLES DOERING, Jr., and HENRY H. DOERING, citizens of the United States, both residents of Oak Park, 5 in the county of Cook and State of Illinois, have invented certain new and useful Improvements in an Apparatus for Dispensing Drinking-Cups and Beverages; and they do hereby declare the following to be a full, 10 clear, and exact description of the invention, such as will enable others skilled in the art to which it appertains to make and use the same.

This invention has for its object to provide 15 an apparatus for dispensing drinking cups and beverages, and consists in the features of construction and combination of parts hereinafter fully described and particularly claimed.

20 The particular object of the invention is to provide a device of the character set forth in which the beverage to be dispensed is first received in a chamber surrounded by a cooling medium in which it is maintained 25 cold and refreshing, and is then fed into another chamber adapted to contain a measured quantity thereof and is thereupon dispensed from the last-named chamber, the dispensing means being coin-controlled.

30 A further object of the invention is to provide a dispensing apparatus of the character set forth in which upon deposit of a coin and the manual actuation of a lever there is first delivered to the depositor of 35 the coin a drinking cup of paper which is preferably folded, and in which upon the actuation of the lever for receiving the cup the measured quantity of liquid paid for by the coin is delivered into the measuring 40 chamber and thereafter upon the return of the lever to its normal position such liquid is drained from said measuring vessel into the cup held below the discharge spout of the device.

45 In accordance with the attainment of the foregoing objects, the invention has for its more particular objects to provide an arrangement of receptacles and valves enabling the successive operations above set forth to be readily, simply and reliably performed as will more particularly appear from the following specification.

A suitable embodiment of the invention is illustrated in the accompanying drawings 50 in which:

Figure 1— is a view in front elevation

of a beverage-dispensing apparatus constructed in accordance with the invention.

Fig. 2— is a top plan view of the same.

Fig. 3— is a view in elevation of one 60 side of the folded drinking cup adapted to be ejected from the apparatus.

Fig. 4— is a vertical section taken on the line 4—4 of Fig. 5—.

Figs. 5— and 6— are horizontal sec- 65 tions taken on the lines 5—5 and 6—6 respectively of Fig. 4—.

Figs. 7— and 8— are fragmentary detail sections showing the coin-receiving means controlling the operation of the 70 device and the discharge therefor, said parts being shown in their different positions.

Figs. 9— and 10— are fragmentary detail vertical sections on the line 9—9 of Fig. 11— showing the parts in their two 75 positions.

Fig. 11— is a fragmentary detail vertical section on the line 11—11 of Fig. 9—.

Figs. 12— and 13— are fragmentary detail vertical sections on the line 12—12 of Fig. 11 showing the parts in two positions.

Figs. 14— and 15— are detail horizontal sections on the line 14—14 of Fig. 16—, showing the three-way valve employed.

Fig. 16— is a fragmentary detail horizontal section on the line 16—16 of Fig. 11— showing the three-way valve illustrated in Figs. 14— and 15—.

Fig. 17— is a view similar to Fig. 9— 90 16— showing the valve in a different position.

The apparatus comprises a suitable housing which, in the instance illustrated, consists of a cylinder 1 closed at top and bottom and which is provided in its upper end portion with a receptacle 2 for ice, the latter being closed by means of a removable cover 3, and is further provided in its upper end portion with the cup ejecting and 100 liquid-dispensing means which will be hereinafter described in detail. The lower end portion of said casing 1 is adapted to receive a receptacle 4 for water from melted ice, and the remainder may be used for storage of bottles of the liquid to be dispensed. Said lower end portion of the said housing is adapted to be closed by means of a door 5 adapted to be locked in any well-known manner.

110 The receptacle 2 is preferably provided with double walls having the spaces between

- the same filled with a non-heat conducting material such as asbestos, or the like, and this may be termed the refrigerating chamber. The latter is provided in its lower end 5 with a tank 7 adapted to contain the liquid to be dispensed. The said tank as shown is relatively small and flat and the ice introduced into the chamber 2 is adapted to rest upon the same to cool the contents thereof.
- 10 Below the same is an open space to receive the water from melted ice which is adapted to absorb the heat from the liquid to be dispensed contained in said tank, and is adapted to be drained off into the receptacle 4 by means of the valve 8 connected to the receptacle 2 by a pipe 8^a. The said tank 7 is adapted to be filled through the vertical tubes 9 provided at their upper ends with funnels 10, the latter being adapted to support inverted bottles 11, shown in Fig. —1—. The said inverted bottles serve to maintain the said tank 7 completely filled with the liquid to be dispensed at all times in a well-known manner, it being obvious, 25 however, that any other suitable means for maintaining a constant supply of the beverage to be dispensed in said tank 7 may be employed in place of the inverted bottles 11.
- 30 The circumferential wall of the housing is provided with two relatively deep recesses 12, each having a flat bottom and convergent side walls. The discharge nozzles 13 for the liquid to be dispensed project into 35 said recesses 12 and the knobs 14 for ejecting the drinking cups and actuating the dispensing mechanism also project into said recesses. Immediately rearwardly of the same and attached to the inner wall of each 40 of said recesses are the containers 15 for drinking cups, the latter being preferably rendered visible through a pane of glass 16 in the said inner wall of each of said recesses 12.
- 45 In describing the invention the routine of the operations will be followed to the end that the invention may be fully understood and its operation comprehended without special review of the latter.
- 50 As shown in Figs. —9— and —10—, the drinking cups 17, shown in detail in Fig. —3—, are disposed flatwise one upon the other within the said receptacle 15, and a weight 18 is disposed upon the top of the 55 pile in order to compress the same upon the cup-ejecting means disposed in the bottom of said receptacle 15. The cup ejecting means comprises a plunger 19 rigid with the knob 14 and projecting into the recess 12, 60 said plunger being slideable in the bottom of the receptacle 15 and being equipped with suitable means for engaging the lowermost cup 17 for ejecting the latter through the slot 20 in the front wall of said receptacle 65 15, which is identical with the inner wall of

the recess 12 in the housing. Said cup-engaging means consists of a flat plate 19^a on the upper surface of said plunger 19, which is preferably provided with a sharp front edge adapted to engage the edge of the flap 19^b at the bottom of the cup 17 and will cause the latter to be moved forward with said plunger 19 through said slot 20. The next higher cup is adapted to abut against the inner face of the inner wall of said recess 12 just above said slot 20 and thus be prevented from being ejected with the bottom cup. Positioned in front of said slot 20 is a projection 22 having an inclined upper face over which the cup is adapted to ride 80 so as to cause the ejected end thereof to project upwardly from the surface of the plunger 19 to enable it to be more easily grasped by the fingers.

The cup is preferably provided with opposed walls of different length so that the upper edge 19^c of one thereof will be overhung by the other 19^d as shown in Fig. —3—. The flap 19^b overlaps the shorter wall, and, in order to insure the ejection of 90 a cup upon each outward movement of the plunger, the plate 19^a is made in the form of a flat spring secured at its forward end to the plunger 19, which forward end forms the projection 21. The rear free end of the 95 plate terminates in a small upwardly extending projection 21^b which is adapted to engage the upper end 19^d of the longer wall of the cup, said projection being normally supported at an elevation above the plunger 100 and held down by the weight of the stack of cups and the follower 18. Thus each cup is engaged at two points and failure of the plunger to eject one thereof at each operation is obviated.

The outward or ejecting movement of the plunger 19 is controlled by means of a coin-controlled apparatus, shown in detail in Figs. —7— and —8—. The coin is deposited in the opening 23 in the inner wall of 110 the receptacle 12 of the housing, said opening or slot 23 communicating with the upper end of a chute 24 which leads to and communicates with a small coin chute 25 carried by the plunger 19. An opening 25^a 115 through the plunger and a slot 26^a in the bottom wall 26 of the receptacle 15 enable the coin received in the chute 25 to project into contact with and rest upon a platform 27 which is pivotally mounted in depending projections 28, and is provided at one side of its pivot with a counterbalancing weight 29 (Fig. 11) which maintains the coin-receiving end portion thereof normally raised. The platform 27 carries a pin or projection 30 having a beveled upper face which is adapted to project through the opening in the bottom plate 26 of the receptacle 15 into one of a series of openings 30^a 120 in said plunger 19 thus preventing the out-

105

110

120

125

130

ward movement thereof until the coin 31 has been deposited and by its weight releases the pin 30 from engagement with the plunger thereby enabling the latter to be moved outwardly to the position shown in Fig. —8—. The slot 26^a in the bottom plate 26 is relatively long and at its forward end registers with the upper end of a chute 32 leading to a coin-receiving receptacle 33 below the said receptacle 15. Upon releasing the pin 30 from engagement with the plunger 19, the latter is moved forward to the position shown in Fig. —8—, carrying the coin with it, and as the coin is drawn forward out of engagement with the counter-weighted platform 27 it drops into said chute 32 and passes into a coin receptacle 33. During the outward movement of the plunger 19 a drinking cup 17 will obviously be delivered to the depositor of the coin. The coin chute is arranged to enable a number of coins to be deposited successively without operating the plunger, and said plunger may then be successively operated until the total number of coins contained in the chute has been exhausted. During the return movement of the plunger the pin 30 by reason of its beveled upper end acts as a ratchet engaging successively in the several openings 30^a thereby preventing repeated partial inward and outward movements of the plunger after depositing only one coin.

During the forward movement of the plunger as above described, a valve is actuated which causes liquid from the tank 7 to pass into a measuring receptacle 34, the latter communicating at its upper end with an air inlet and outlet tube 34^a which projects above the greatest level of liquid adapted to be contained in the tank 7 and the tube or tubes 9 through which the said tank is fed. Said communication is effected through the pipes 35 and 36, the former leading from the lower part of the tank 7 to a T head 35^b and the latter communicating with the casing 37 of a three-way valve, there being one branch 36 leading to each of the two valve casings 37. The valve employed is preferably of the type usually termed cocks. The said housing is slightly conical and receives the similarly shaped valve plug 38 which is provided with a passage 39 extending from its larger end to the circumferential face thereof to enable the same to register with two openings 40 and 41 in the valve casing. The pipe 36 is connected to one end of said valve casing and communicates at all times with the opening 40 in the valve casing 37. The passage 39 in the valve plug is Y-shaped, that is to say, it has two outlets or branches 42 and 43 adapted to communicate with said respective openings 40 and 41, the latter and said passages 42 and 43 being relatively arranged so that when the passage 43 reg-

isters with the opening 41 the passage 42 is out of communication with the opening 40, as more particularly illustrated in Figs. —14— and —15—.

A pipe 44 connected with one branch of 70 said valve casing 37 connects the latter with the said measuring receptacle 34, while the opening 41 in the valve casing is connected by means of the pipe 45 with the discharge nozzle 13 in the recess 12 of the 75 housing.

The said valve plug 38 is provided with an operating handle 46 equipped at its outer end with a projection 46^a which engages in the bifurcated end of a downwardly extending arm 47 rigidly carried by the plunger 19 and said valve is adapted, during the forward movement of said plunger 19 to eject a cup, to be turned so as to cause the pipe 36 to communicate with the pipe 44 thus 85 causing liquid to pass into the measuring receptacle 34. The latter now fills with the beverage 7 to be dispensed and as the plunger is moved back to its normal or inner position the said valve plug is turned to the 90 position shown in Fig. —9—, and also shown in Figs. —15— and —17—, thus causing the measuring receptacle 34 and the pipe 44 to communicate with the pipe 45 leading to the discharge nozzle 13. It will be noted that in 95 the first position to which the valve is moved by the outward movement of the plunger the pipes 44 and 45 do not communicate with each other and that in the last-named position of the valve the pipes 36 and 44 100 do not communicate with each other. The admission of liquid to and the draining thereof from the said receptacle 34 is permitted by the ready escape of displaced air and its re-admission through the pipe 105 34^a. Wear on the valve is automatically taken up by the spring 35^a interposed between the handle 46 on the valve-stem and a washer on the opposed end of the valve casing.

The depositor of the coin having first obtained a cup to receive the beverage by pulling the plunger 19 to the outer limit of its movement, proceeds to open the cup preparatory to filling the same with the beverage 115 and having opened the same holds it below the spout or nozzle 13 and thereupon returns the plunger to its normal or inner position whereupon the liquid is drained from the receptacle 34 into the cup.

In order to check up the number of said cups sold and the amount of beverage dispensed, we provide an automatic counting mechanism 48 of any well-known character having an operating lever 49, the outer end 125 of which is disposed in the path of two projections 50 and 51 (Fig. 9) on the plunger 19, one of said projections serving to throw said lever forward as the plunger moves outwardly and the other of same serv- 130

ing to return said lever to its normal position as the plunger is moved to its inward position.

All of the operating parts of the mechanism, except those specifically described as exposed, are accessible only through openings provided with locks, the keys of which will be in possession of the proprietor or his agent so that access may be had thereto only by authorized persons. The said means of access are not particularly illustrated as they are commonly used and constitute no feature of the invention.

We claim as our invention:

15 1. A liquid dispensing apparatus comprising a container for drinking cups, a reservoir for liquid, an auxiliary container for a cupful of liquid, a discharge spout for liquid, a valve arranged to alternately connect said auxiliary container with said reservoir and said discharge spout, a manually operable plunger for ejecting cups consecutively from said container, and connection between said plunger and said valve whereby the latter is moved to a position connecting the auxiliary container with said reservoir as the plunger ejects a cup.

20 2. A liquid dispensing apparatus comprising a container for drinking cups, a reservoir for liquid, an auxiliary container for a cupful of liquid, a discharge spout for liquid, a valve arranged to alternately connect said auxiliary container with said reservoir and said discharge spout, a manually operable plunger for ejecting cups consecutively from said container, and connection between said plunger and said valve whereby the latter is moved to a position connecting the auxiliary container with said reservoir as the plunger ejects a cup, said valve being moved to a position to connect said auxiliary container with said discharge spout as said plunger is returned to its normal position.

25 3. A liquid dispensing apparatus comprising a container for drinking cups, a reservoir for liquid, an auxiliary container for a cupful of liquid, a discharge spout for liquid, a valve arranged to alternately connect said auxiliary container with said reservoir and said discharge spout, a manually operable plunger for ejecting cups consecutively from said container, and connection between said plunger and said valve whereby the latter is moved to a position connecting the auxiliary container with said reservoir as the plunger ejects a cup, said valve being moved to a position to connect said auxiliary container with said discharge spout as said plunger is returned to its normal position, and releasable means arranged to engage said plunger against cup ejecting movement from its last-named position.

4. A liquid dispensing apparatus comprising a container for drinking cups, a reservoir for liquid, an auxiliary container for a

cupful of liquid, a discharge spout for liquid, a valve arranged to alternately connect said auxiliary container with said reservoir and said discharge spout, a manually operable plunger for ejecting cups consecutively from said container, and connection between said plunger and said valve whereby the latter is moved to a position connecting the auxiliary container with said reservoir as the plunger ejects a cup, said valve being moved to a position to connect said auxiliary container with said discharge spout as said plunger is returned to its normal position, and releasable means controllable by the operator arranged to lock said plunger against cup ejecting movement from its last-named position.

5. A liquid dispensing apparatus comprising a housing, a reservoir for liquid, a liquid cooling chamber within the housing connected with said reservoir, an auxiliary liquid measuring chamber within the housing connected with said cooling chamber, a manually operable valve within said housing interposed in said connection, means manually operable from the exterior of the casing for moving said valve to alternately connect said measuring chamber with said cooling chamber and said discharge spout, and means associated with said manually operable means for automatically supplying a drinking cup as said valve is moved to the first-named position.

6. A liquid dispensing apparatus comprising a housing, a reservoir for liquid, a liquid cooling chamber within the housing connected with said reservoir, an auxiliary liquid measuring chamber within the housing, means connecting the measuring chamber with said cooling chamber, a manually operable valve within said housing interposed in said connection, a discharge spout also connected with said valve, means manually operable from the exterior of the housing for moving said valve to alternately connect said measuring chamber with said cooling chamber and said discharge spout, means associated with said manually operable means for supplying a drinking cup as said valve is moved to the first-named position, and releasable means controllable by the operator for locking said manually operable means against the aforesaid movement.

7. A liquid dispensing apparatus comprising a housing, a refrigerating chamber therein, a container for water within said chamber, a reservoir for water connected with said container, a receptacle for a measured quantity of liquid connection between said container and receptacle, a discharge spout, connection between the latter and said receptacle, a valve interposed in said connections and adapted to alternately connect said receptacle with said container and said discharge spout, said receptacle and said

valve disposed within the housing, means operable from the exterior of the housing for actuating said valve, and means associated with said valve-actuating means for supplying a drinking cup each time the valve is operated to connect the receptacle with the container.

8. A liquid dispensing apparatus comprising a housing, a refrigerating chamber therein, a container for water within said chamber, a reservoir for water connected with said container, a receptacle for a measured quantity of liquid connected with said container, a discharge spout connected with 10 said receptacle, a valve interposed in said connections and adapted to alternately connect said receptacle with said container and said discharge spout, said receptacle and 15 said discharge spout connected with said valve.

said valve disposed within the housing, means operable from the exterior of the housing for actuating said valve, means associated with said valve-actuating means for supplying a drinking cup each time the valve is operated to connect the receptacle with the container, and releasable means controllable by the operator for holding said valve-actuating means against movement.

In testimony whereof we have signed our names in presence of two subscribing witnesses.
